ASH SIFTING DEVICE

Joseph G. Fakult, Cleveland, Ohio

Application November 20, 1935, Serial No. 50,793

3 Claims. (Cl. 126—244)

This invention relates to an ash-sifting and unburned fuel discharge device for coal stoves, furnaces and heaters and the ash-sifting device according to the invention is adapted to be disposed in a furnace etc. under the grate bars thereof. As well known, ashes passing through the now commonly used rotatable or shiftable grate bars of a furnace contain a high percentage of unburned fuel, as the grate bars are widely spaced to permit of clinkers and other unburnable residue being crushed and discharged into the ash pit of the furnace. The sifting of ashes in order to separate the unburned fuel therefrom is very inconvenient, dusty and unwelcome, therefore furnace operators rather waste the unburned fuel than go to the inconvenience of sifting the ashes.

It is the primary object of this invention to provide a simple and efficient ash-sifting and unburned fuel discharge device, which is adapted to be disposed and operated in a furnace so that all dust and dirt will be retained in the furnace, and which is adapted to forwardly discharge the sifted unburned fuel through the ash door of the furnace into a discharge receptacle, extended into the furnace and cooperating with the ash sifter during discharge operations.

Another object of the invention is to provide an ash sifter of the above named character, which can readily and easily be mounted in a furnace without any change of the stove structure and which is operated independently of the grates of the stove.

A further object of the invention is to provide an ash sifter of the above named character so constructed and mounted in the furnace below the grates thereof that all air entering through the ash door contacts with the sifting element and is preheated thereby in order to supply preheated air to the fire pot and effect a better combustion of the fuel.

With these and incidental objects in view, the invention consists in certain novel features of construction and combination of parts, the essential elements of which are set forth in the appended claims; and a preferred form of embodiment of the invention is hereinafter shown with reference to the drawing accompanying and forming part of this specification.

In the drawing Figure 1 is a central vertical section through the lower part of a domestic furnace, having an ash sifter according to the invention mounted therein.

Figure 2 is a top plan view of the reciprocatory ash sifter member of the ash sifter shown in Figure 1.

Figure 3 is a perspective view of one of the suspension members of the ash sifter.

Figure 4 is a perspective view of the ash sifter pan and

Figure 5 is a perspective view of the ash sifter discharge receptacle cooperating with the ash sifter during discharge operations.

Referring to the drawing the reference numeral 2 designates a stove or furnace casing, which may be of any desired size, form and material, and, as usual, has in its lower portion an ash pit 3, equipped with a horizontally hinged draft controlling door 4. This hinged door is part of a larger door 5, which, as customary, is hinged to the casing 2, so as to swing about a vertical axis 15 and expose a large part of the ash pit for cleaning purposes. The casing 2 is provided with bearings 6 and 7 in which are rotatably mounted grate bars 8, provided at their front ends with extension rods 9, which rods are adapted to be operated by a crank or operating member inserted through an opening in the door 5, all as presently practiced. The furnace casing supports the customary combustion chamber 10, arranged above the grate bars 8.

In accordance with the present invention an elongated sifting member 11 is suspended from the grate bars 8 by means of suspension elements 12. These elements embody a double hook-shaped attachment portion 14, adapted to be hooked to the front or rear ends of grate bars 8, as indicated at 15 and 16, and a chain portion 17, adapted to be hooked into and securely interlocked with the perforated bottom wall 18 of member 11, enlarged holes 19 being provided for this purpose. As shown, there are three suspension elements 12, which provide a three point suspension for the member 11 and insure a free reciprocatory movement of member 11 if so desired. The elements 12 are so secured to member 11 that the two front elements 12 and the single rear element 12' converge toward each other. This arrangement effects a tilting of the member 11 toward the rear, when same is shifted rearwardly and a tilting toward the front, when member 11 is shifted toward the front. The element 11 which is preferably made of perforated sheet metal or steel, the perforations being indicated at 20 and consisting of holes approximately one eighth of an inch in diameter, is flanged as at 21 at its rear and the two sides. The front portion of the element 11 is narrowed to approximately one third of the width thereof to provide a narrowed portion 22, which portion permits of

the sifted coal residue being readily discharged, as will be described hereinafter.

The portion 22 carries at its front end pivoted thereto a threaded operating member 23 adapted to swing in a horizontal plane, which member is bent at its outer end to form a loop 24, permitting the connection of a hook thereto if so desired. The body of member 23 carries nut members 25 which are threadedly engaged with said body and longitudinally adjustable thereon to permit of proper adjustment of the reciprocatory movement of member 11, as will be later described.

A flat ash pan 27 seated on the base plate 28 of the furnace receives the ashes which fall through the perforations 29 in member 11 during sifting operations. This pan can readily be removed through the door 5.

During sifting operations the door 5 is in closed position and the door 4 is open, so that the member 23 can be extended through the opening covered by the door 4 for manually reciprocating the member 11 during such sifting operations.

When the ashes on the member 11 have been thoroughly sifted, then a discharge receptacle 29 is inserted into the opening covered by the door 4, which receptacle embodies a box-like container 30 open at its front end and partly open at its top 31. This container is provided at its top and spaced from its front end with an angular cross piece 32, rigidly secured thereto and extending at opposite sides beyond the side walls 33 of the container 30. The cross piece 32 limits the inward movement of the discharge receptacle into the draft controlling opening covered by the door 4, furthermore guides the member 23 during its reciprocatory movement and finally stops the forward movement of the member 11 during discharge operations. Thus the cross piece 32 is provided with a vertical narrow slot 34 permitting the member 23 to be extended therethrough and to be guided thereby, but limiting the longitudinal movement of said member and the member 11, when the nut members 25 on member 23 engage the cross piece 32. When the forward movement of the member 11 is suddenly stopped, then the sifted residue of the ashes continues to travel on member 11 and finally will be discharged into the

container 30, keeping in mind, that the member 11 at the end of its forward stroke is forwardly tilted. A handle 35 on container 30 permits of proper handling of the discharge receptacle 29.

Having thus described my invention, what I claim is:

1. In a furnace having a grate and an ash-pit below the grate, an ash sifting and coal residue discharge device comprising a perforated chute-like sifting member arranged within the ash-pit of said furnace, converging suspending means for said sifting member adapted to effect tilting of said member when reciprocated, operating means attached to the front end of said sifting member for manually reciprocating same, and guiding means for said operating means co-operating therewith in limiting reciprocatory movements of said sifting member.

2. In a furnace having a grate and an ash-pit below the grate, an ash sifting and coal residue discharge device as described in claim 1, wherein the operating means for the sifting member embody means axially shiftably secured to said operating means adapted to co-operate with said guiding means in stopping movement of said sifting member in a predetermined position.

3. In an ash sifting and coal residue discharge device for a furnace the combination of a perforated, flanged sifting member having a chute-like extension at its discharge end, means suspending said member for reciprocatory movements, and operating means attached to the extension of said sifting member for manually shifting same in opposite directions, with a coal residue receptacle extended into the furnace below the extension of said sifting member, said receptacle having means for guiding the operating means of said sifting member, and means on the operating means of said sifting member co-operating with the guiding means of said receptacle in stopping the movement of said sifting member toward said receptacle when said sifting member is in a predetermined position to effect discharge of coal residue from said sifting member through its extension into said receptacle.

JOSEPH G. FAKULT.
